ELECTRIC LAMP

Harold Douglas Wilson, Gloucester, and Walter N. Heath, Rockport, Mass., assignors to Birds-eye Electric Company, Dover, Del., a corporation of Delaware

Application June 7, 1937, Serial No. 146,750

10 Claims. (Cl. 176—32)

This invention relates to the manufacture of incandescent electric lamps and consists in an improved construction mechanically uniting the glass bulb with its metal base. It has been the usual practice to depend upon cement for attaching the base to the neck of the bulb, but in the case of the higher wattage lamps and particularly in lamps employing a reflecting surface upon or within the bulb, a high degree of heat is developed which is likely to impair the adhesive properties of the cement and to result in a looseness which sometimes permits separation of the bulb from the base.

The general objective of our invention is the provision of a mechanically attached base which will obviate the difficulties above discussed, and which may be achieved with very little departure from the present standard practice of basing incandescent lamps. In one aspect the invention consists in an anchor member or clip which may be secured in position upon the end of the bulb neck or adjacent thereto by connection with the lead wires, or other wires sealed into the bulb, and thus held in position upon the bulb, and being also shaped to make engagement with the metal base. Such an anchor member may be embedded in the cement employed in commercial basing operations without requiring any modification of the operation. Although under conditions of excessive heat the cement may completely lose its adhesive properties, it does not physically disintegrate, and so is still capable of serving as a filler or positioning medium holding the anchor member firmly against displacement.

The anchor member herein shown for illustrative purposes may be constructed advantageously from a thin metal stamping and a washer or disk of heat-resisting insulating material, the assembled member being provided with spaced passages for the lead wires, and in some cases with an aperture for the end of the exhaust tube which usually projects somewhat beyond the end of the bulb neck. The metal portion of the anchor member is provided with inclined outwardly extending projections or prongs of a resilient character which are adapted positively to engage the threads of the base or other irregularities in its surface. Preferably and as herein shown, the metal portion of the anchor member is cut away so as to clear at least one of the lead wire passages, with the result that the lead wires are insulated from each other at this point and also positively spaced from each other. By threading the anchor member over the end of the ex-

haust tube the parts may be maintained in concentric relation and the lead wires prevented from being short-circuited even if the bulb should be twisted with respect to its base.

While our invention in its ultimate form is embodied in an incandescent lamp, in another aspect it comprises as a distinct article of manufacture, a novel anchor device comprising a united insulating disk and metal stamping having one wire passage in the combined disk and stamping, and another wire passage in the disk alone. As herein shown the disk and segment are united by metallic eyelets, which beside affording satisfactory fastening means, supply a metal body adjacent to the lead wires which facilitate the application of solder thereto if that material is to be used in securing the anchor member to the bulb.

These and other features of the invention will be best understood and appreciated from the following description of a preferred embodiment thereof, selected for purposes of illustration and shown in the accompanying drawing in which—

Fig. 1 is a view in elevation, partly in section, showing the base in its assembled relation upon the neck of the bulb.

Fig. 2 is a similar view in perspective with the metal base omitted.

Fig. 3 is a sectional view of the anchor member, and

Fig. 4 is a view in perspective of the component parts of the anchor member in separated relation.

The lamp partially shown in Figs. 1 and 2 comprises a bulb 16 of usual commercial construction terminating in a neck 11 of reduced diameter. Within the neck is disposed the usual mount 12 terminating at its inner end in a press in which are sealed the two lead wires 13 and 14. At its outer end or flare the mount 12 is sealed to the end of the neck 11, a circular bead 15 including the line of seal. Within the hollow mount 12 is arranged the exhaust tube 18, and this, after it is sealed off in the operation of exhausting the bulb, projects outwardly beyond the plane of the bead 15.

The lamp includes in its structure a metal base 17 of conventional shape, having threads formed in its side walls and an insulated end terminal for one of the lead wires. The base 17 encloses the bead 15 of the neck with substantial clearance and is held in position upon the neck 11 by cement 18, as well as by the holding action of the anchor member, which will now be more particularly described.

As herein shown the anchor member of the clip includes in its structure a flat circular washer or perforated disk 20 of insulating material such as mica or hard fibre. In exterior diameter it 5 preferably coincides substantially with the exterior diameter of the bead 15 and its interior perforation is of sufficient diameter to permit the passage of the exhaust tube 16 with ample clearance as shown in Fig. 2. In one side of its body 10 the disk 20 is provided with a tubular eyelet 21, which forms one of the lead wire passages.

The metallic portion of the anchor member comprises a thin metal stamping 22 which is generally circular or segmental in shape, having 15 a recess 23 therein preferably coinciding partially with the annular wall of the perforation in the disk 20 and of sufficient width to clear the eyelet 21 by a substantial margin. The stamping is provided also with inclined outwardly extending 20 prongs or teeth 24 spaced about its periphery and diverging outwardly so as to clear the outer circumference of the disk 22. The prongs 24 are 25 preferably somewhat resilient in character and are disposed with their outer ends in a circle of larger diameter than the base 17 but so that they may yield and temporarily contract when the base is forced over them in the basing operation. The metal stamping 22 and the insulating disk 20 are united by the three eyelets 25, one or more 30 of which may form lead wire passages through the anchor member at spaced points. Any one of the eyelets 25 may be used as a lead wire passage in combination with the passage of the eyelet 21 which, as already explained, is completely 35 insulated from the three passages of the eyelets 25.

In the present commercial system of basing lamp bulbs a charge of thermoplastic cement is supplied to the base and then the base is applied 40 to the neck of the bulb and held in position while the cement is heated until a union is formed with the glass of the neck. In accordance with 45 our invention no departure is required from this commercial procedure, although it is supplemented by the step of assembling and fastening the anchor member in position. This may be done as suggested in Fig. 2 by threading the lead wires 13 and 14 through the passages of the eyelets 21 and 25 and positioning the anchor member 50 concentrically upon the end surface of the bead 15 with the end of the exhaust tube 16 passing through its central perforation. A drop of solder 26 is now applied to both lead wires just above the flange of the respective eyelets 21 and 25 and in this manner the anchor member 55 is positively and permanently held in position fast upon the bead 15. The base 17 is now provided with a charge of cement in plastic condition and pressed upon the end of the neck 11. 60 In this movement the corrugations or threads in the inner wall of the base are advanced beyond the ends of the outwardly extending prongs 24. The latter are first contracted by the relatively 65 stiff cement in the base and then, as the cement is softened by heat, they spring out resiliently from the neck and snap into one or another of the corrugations, becoming mechanically interlocked therewith so that it is impossible to 70 retract or remove the base without stretching or breaking the lead wires. In this operation the plastic cement 18 is caused to flow about the clip so that the prongs thereof become embedded in cement as best shown in Fig. 1. The cement hardens within a short time and acts effectively 75 to prevent displacement of the clip and particu-

larly to prevent any disturbance of the interlocking engagement between the prongs 24 and the surface irregularities provided by the corrugations in the walls of the base. The result is that 5 the interlocking engagement of the parts cannot be disturbed so long as the cement acts as a filler. If the cement is heated to the point that it loses its adhesive properties, it is still effective indefinitely as a filler and positioning 10 medium and the mechanical connection of the metal base and the glass neck is permanently maintained.

While we have shown lead wires soldered to or above the eyelets of the passages, any wires sealed in the bulb or mount would serve as well, and any 15 form of mechanical connection may be substituted for solder within the scope of the invention. Also, it is not necessary that the anchor member be maintained in direct engagement with the end of the bulb neck and if desired any sort of 20 spacing element may be interposed between the two.

Having disclosed our invention and described a preferred embodiment thereof for illustrative purposes and not by way of limitation, we claim 25 as new and desire to secure by Letters Patent:

1. An electric lamp having a bulb with lead wires sealed in its neck portion, a base, and a clip having a flat heat insulated body bearing upon the end of the neck and held in position 30 thereon by mechanical connection with the lead wires and having base-engaging projections.

2. An electric lamp including in its structure a bulb having a circular bead at the end of its neck, a flat anchor piece held rigidly against 35 the outer annular surface of the bead and having outwardly projecting prongs, and a metal base held upon the neck of the bulb by interlocking engagement with said prongs.

3. An electric lamp including in its structure 40 a bulb having a hollow mount sealed within its neck and presenting a rounded annular bead at the end of the neck, lead wires passing out through the mount, a disk-shaped clip having spaced radial projections about its periphery and 45 being located upon the bead and held in place by connection with the lead wires, and a metal base enclosing the clip and engaged by projections thereon.

4. An electric lamp having a bulb with lead 50 wires sealed therein, a clip comprising an insulating disk having a toothed metal segment fast thereto, a wire passage through the disk spaced from said metal segment, means for connecting a lead wire and said clip, and a base engaged 55 by the teeth of said segment.

5. In an electric lamp, an anchor device comprising a united insulating disk and metal segment, the device having a wire passage in the combined disk and segment and another wire 60 passage in the disk alone.

6. In an electric lamp, an anchor device comprising an insulating disk having a wire passage, a metallic segment having radially projecting prongs, and an eyelet uniting said disk and 65 segment and forming another wire passage in the device.

7. In an electric lamp, a bulb having lead wires sealed therein and a metallic base upon 70 its neck portion, and an anchor member comprising an insulating disk having a wire passage and a sheet metal piece coextensive with a portion of said disk and clearing said wire passage, the sheet metal piece being extended beyond the periphery of the disk to engage the base and one 75

of the lead wires having means adjacent to said wire passage for holding the anchor member in contact with the neck of the bulb.

8. An electric lamp having a bulb with a hollow mount sealed into its neck and an exhaust tube and lead wires passing out of said mount, in combination with a metallic base and an anchor member encircling the exhaust tube, engaging the base and being held in position against the end of the bulb neck by connection with the lead wires.

9. An electric lamp having a bulb with a metallic base and an exhaust tube terminating within the base, and a perforated anchor mem-

ber threaded over said exhaust tube and having wire passages spaced from the tube and base engaging projections, and lead wires passing from the bulb and connected to the anchor member to hold the latter in place.

10. An electric lamp having a bulb with wires sealed within its neck portion, a metallic base containing cement in contact with the bulb, and a clip held adjacent to the end of the neck by connection with said wires and having projecting portions which are embedded in said cement and engage the base to hold it against separation.
